UNITED STATES PATENT OFFICE.

HASTINGS JOHN HOLFORD, OF ADDISCOMBE, ENGLAND, ASSIGNOR OF TWO-THIRDS TO
PERCY PORTWAY HARVEY, OF LONDON, ENGLAND.

CENTRIFUGAL SEPARATING APPARATUS.

Application filed September 9, 1925, Serial No. 55,272, and in Great Britain January 8, 1925.

This invention relates to centrifugal separating apparatus for various purposes but more especially intended for dealing with crude or impure oils (petroleum or vegetable) of various densities for the object of removing solid or liquid impurities, and we shall describe the apparatus as applied to the treatment of oils. The chief object of the invention is to facilitate the efficient separation of the ingredients of the liquids and in the case of liquids containing solid impurities to provide for a suitable method of collecting the said solid impurities in the apparatus. A further object is to allow the interior of the apparatus to be readily reached and the parts separated for removal of any accumulation of material separated from the liquid.

According to this invention the rotating bowl, to which the oil to be treated is fed, is provided with a number of vertical tangent plates mounted in a cylindrical group between top and bottom rings or discs, above the said group of discs being preferably fitted a deflecting plate or plates directing the separated ingredients into separate discharge apertures. The tangent plates are preferably secured alternately to the top and the bottom discs or rings to permit of separation of the plates in two groups which are normally interleaved. In centrifugal apparatus for dealing with impure oils frequent cleansing is necessary and the ready separation of the plates greatly facilitates the cleansing operation. For lighter oils the plates are numerous and closely spaced while for heavier oils fewer plates are employed. If waxy matter such as paraffin wax forms part of the crude oils or mixtures the plates may serve to collect the solid material and may be of greater length than in apparatus employed for purely liquid mixtures. The plates are mounted to form tangents to a circle concentric with the bowl and the oil enters between the adjacent inner edges of the plates and flows through the radially expanding chambers formed by the plates, which are provided with rearwardly directed lips at their outer edge.

Above the plates, the upper edges of which are cut to form a cone, are placed a series of spaced conical deflecting plates or discs between and over which the oil passes

upwardly to the discharge or discharges. 55 The conical plates serve to intercept light solid particles or impurities which are found to be carried over by the liquid and would otherwise be discharged with it. The vertical tangent plates are also cut away at the bottom to form a central conical space into which the oil is fed before separation through a vertical tube with vertical slots for spreading the oil over the base of the bowl.

In order that the said invention may be clearly understood and readily carried into effect, the same will now be described more fully with reference to the accompanying drawings, in which:—

Figure 1 is a vertical section of the upper part of the separating apparatus, the lower portion containing the driving mechanism, not shown as this forms no part of the present invention.

Figures 2 and 3 are, respectively, a vertical section and a sectional plan of the central supply tube, which is shown integral with the base of the bowl.

Figures 4 and 5 are views showing the construction of bowl;

Figures 6 and 7 are views showing the arrangement of tangent plates; and

Figures 8 and 9 are, respectively, a section and a plan of the conical deflecting plates.

A is the upper portion of the base or main frame of the machine. B is the rotating bowl, comprising a cylindrical wall with conical top b, mounted on the base b'. C is a hopper through which the oil or other liquid is supplied under the control of the valve or cock c and strainer c'. The valve c is provided with an operating handle c², at the top of the hopper. D, D' are covers forming the upper casing of the apparatus; on the top d is a cylindrical neck d' carrying the hopper C. E, E' are the vertical tangent plates mounted between the top and bottom rings e, e' and nearly filling the lower part of the bowl B. F, F' are the conical deflecting plates or discs above the plates E. G is a vertical distributing tube for the liquid to be treated. H is a vertical driving shaft extending from the driving gear in the lower part of the apparatus, not shown, into the lower part g of the tube G and engaging with the

said tube which in the construction shown is made in one piece with the base b' of the bowl.

- A small space is left between the periphery of the group of plates E, E and the inner surface of the bowl B and the upper edges of the plates E are cut at an angle to form a somewhat flat cone as shown in Figures 1 and 6, while the lower edges extend downwardly in wing form below the ring e' and the inner edges of the extended portions are cut at an angle to provide a central conical recess e^2 . Alternate plates are secured to the peripheral bottom ring e^3 which spaces them apart and the outer edges e^4 are bent back as shown in Figure 7. The remaining interleaved set of plates is secured to the top ring e and merely rests at the bottom in notches in the ring e^3 , while the first mentioned set has its upper end retained in notches in the ring e . Above the conical upper face of the said group of plates is fitted the series of spaced conical deflecting plates F, F', the cone angle being the same as that of the said upper face, and the oil passes upwardly from the top edge of the vertical plate group E past an internal flange b^2 on the bowl and between the successive deflecting plates F, F' to the discharges b^3 , b^4 arranged at different levels in the upper reduced end of the bowl cover or top b . The discharge openings at different levels serve for liquid of different densities, which pass into the annular channels formed by the succession of casing covers D, D' provided with outlet channels d^2 , d^3 for the different liquids discharged, two covers and outlets being shown in the example illustrated.
- It has been found in dealing with crude oils and other impure substances that light solid particles or impurities are carried outwardly by the liquid passing to the periphery of the bowl B through the group of plates E with the result that the liquid discharged through the apertures b^4 carries objectionable impurities if these are not intercepted. It has further been found that such impurities are intercepted by causing the liquid prior to its final discharge to pass between a succession of plates such as F, F', the impurities carried mechanically with the liquid accumulating under the conical deflecting plates F' which lie above the separating plate F, the accumulated impurities being removed at intervals when cleaning out the apparatus. The conical deflecting plates F' therefore play a material part in improving the resulting separated product.
- The oil is supplied to the centrifugal bowl B from the hopper C or other container at a regulated rate through a vertical inlet pipe d^2 which enters the vertical tube G passing through the central space of the group of vertical plates E, the vertical tube

G terminating in a central conical projection b^5 on the base b' of the bowl. The tube G is cut with a number, say four, of vertical slots g' having chamfered edges g^2 , the slots terminating in the upper end of the conical base member b^5 , and a sleeve e^5 carried by the vertical plates E through the rings e , e' encircles the tube G and has a conical end e^6 extending over the top of the cone b^5 and leaving a space for the escape of the oil into the bowl, the oil being downwardly directed over the surface of the base b' of the bowl and rising up between the vertical tangent plates E. The ring e forms a seat for the perforated flanged end of the tube f belonging to the bottom conical deflecting plate F so that the plates F, F' are mounted in a readily removable manner on the sleeve. The plates F, F' are spaced apart by the ribs f' and the upper plates F' have perforated inner flanges f^2 through which the liquid passes.

The bowl is of any convenient construction but a suitable arrangement is to fit the bowl body at its lower edge on to a rubber ring b^6 lying between the outer flange of the base b' and a small internal flange b^7 . The outer casing of the apparatus comprises the casing covers D, D' already referred to, fitted to the base A into which the lower part of the bowl extends. All the parts are constructed so as to separate and allow of ready access to the interior of the apparatus. The liquids of different densities rise in the bowl through the vertical tangent plates, the heavier ingredient being driven outwardly into the space between the periphery of the said plates and the wall of the bowl, while the lighter ingredient tends to separate towards the axis and by the time the mixed liquid has reached the upper edges of the tangent plates the ingredients are practically separated, the heavier passing up to the lower discharge while the lighter passes under the bottom plate F through the annular channel between the tube f and the sleeve e^5 and thence to the upper discharge. Liquid mixtures, emulsions or suspensions of more than two ingredients of different densities can be dealt with by providing the requisite number of discharge openings and employing the conical plates to effect intermediate separations.

In separating finely divided solids from liquids it is found that the solids instead of being thrown out to the periphery of the bowl tend to cling to the inner portions of the plates towards the base of the bowl. This is particularly important in separating waxy ingredients from oils containing them.

What I claim and desire to secure by Letters Patent of the United States is:—

1. In centrifugal apparatus, a rotatable bowl into which the liquid to be treated is fed, a set of vertical plates forming a cylin-

drical group within the said bowl and rotating with it, the upper edges of the said plates sloping to form a conical group face, a plurality of conical deflecting plates fitted in parallel formation above the conical face of the group of vertical plates and members spacing the said conical plates apart.

2. In centrifugal apparatus, a rotatable bowl into which the liquid to be treated is fed, a series of vertical plates forming a cylindrical group within and rotating with the bowl and annular securing members at top and bottom of the said group of plates, alternate plates being secured respectively to the upper and the lower annular members whereby the plates may be separated on opening the apparatus into two groups which are normally interleaved.

3. In centrifugal apparatus, a rotatable bowl into which the liquid to be separated is fed, a group of vertical plates within the bowl and rotating with it, and a succession of transverse deflecting plates fitted in parallel formation above the said group of vertical plates and members spacing the said transverse deflecting plates apart.

4. In centrifugal apparatus, a rotatable

bowl into which the liquid to be treated is fed and a series of spaced vertical plates within the said bowl forming a cylindrical group within and rotating with the bowl, which plates are cut away at the bottom to form a free central space into which the liquid is fed before passing outwardly between the said plates which central space is open to the spaces between the vertical plates to provide for direct outward flow of liquid from the said central space.

5. In centrifugal apparatus, a rotatable bowl into which the liquid to be treated is fed, the base of the said bowl having a conical boss, a slotted vertical distributing tube terminating in the said conical boss and having the vertical slots of the tube extending through a part of the said boss one edge of each of the said vertical slots being chamfered in the direction of rotation, and a sleeve fitted around the said distributing tube and terminating at the said conical boss immediately above the lower end of the slots so as to direct the oil passing through the slots over the base of the bowl.

HASTINGS JOHN HOLFORD.
